UNITED STATES PATENT OFFICE.

CHARLES H. JENKINS, OF BELLEVILLE, NEW JERSEY, ASSIGNOR TO NEWMAN CLOCK CO., OF NEW YORK, N. Y., A CORPORATION OF NEW YORK.

CARRYING-POUCH FOR WATCHMEN'S TIME-REGISTERS.

1,172,460.

Specification of Letters Patent. Patented Feb. 22, 1916.

Application filed January 5, 1912. Serial No. 669,706.

To all whom it may concern:

Be it known that I, CHARLES H. JENKINS, a citizen of the United States, residing at Belleville, county of Essex, and State of New Jersey, have invented certain new and useful Improvements in Carrying-Pouches for Watchmen's Time-Registers, of which the following is a full, clear, and exact description.

10 This invention, which forms the subject matter of this application, relates to carrying pouches for watchmen's time registers, one object of which is to provide an improved pouch or carrying case for the clock 15 for the purpose of protecting the latter from injuries from the weather or other agencies while the watchman is making his detour. Pouches of this character have formerly been gashed in the upper portion thereof 20 and through these gashes protrude means which are secured to the clock casing and which serve as connections for carrying straps. In using these older pouches in rainy weather the water runs down the 25 straps and the gashes serve as avenues through which the water runs into and about the clock casing.

It is one of the principal objects of this invention to so connect the clock to the pouch 30 and the pouch to the carrying straps that the above difficulties are avoided.

A further object consists in so connecting the clock to the pouch that all liability of the clock falling therefrom is avoided.

35 A further object of the invention consists in providing the pouch itself with a strap which, in addition to possessing the advantages detailed above, will also maintain the pouch in upright position when being carried about in use.

Still further objects of the invention will appear from the detailed description given below and from the claims appended hereto.

Referring to the drawing which shows the 45 preferred embodiment of my invention Figure 1 shows a carrying pouch with a watchman's clock secured therein, said pouch being in open position. Fig. 2 shows the pouch in closed position. Fig. 3 is a sectional view of the body portion 11 and of

the face of the clock showing a different method of securing the clock and pouch together. Fig. 4 is a front view of the device shown in Fig. 1.

The reference numeral 10 designates the 55 outer casing or cover portion of the pouch into which the inner casing or body portion 11 is adapted to telescope. The body portion is suitably hinged as at 12 to the cover portion. All these parts are made of leather 60 the hinge itself being suitably riveted or otherwise secured to the two portions. Within the body portion 11 is a watchman's clock 13 secured thereto by means of the screw-threaded and removable fastening 65 means 14 passing through perforations in the body portion 11. As here shown two such means are provided with conical heads adapted to fit in conical sockets provided in the washers 15. These washers are rather 70 large and serve to clamp a substantial portion of the pouch which immediately surrounds the perforations. The screw-threads of the fastening means 14 engage with corresponding threads in the casing of the clock 75 13 and fixedly secures the latter to said pouch.

From the above description it will be apparent that the clock is not exposed at all to the elements. Heretofore it has been customary to provide the clock casing with protruding rings to which the carrying strap is directly connected. This construction necessitates the formation of large holes through both the cover and body portions of 85 the pouch through which the rings project. Such constructions are detrimental to the clock itself, especially in rainy weather, as the water will flow in large quantities down the straps thence to the clock mechanism 90 which is exposed by said perforations. With my improved construction I do away with all perforations in the cover and body portions, excepting the perforation, not shown, at the bottom through which the recording key is insertible, secure the clock firmly to the body portion, and connect the carrying means directly to the cover portion. Inasmuch as the clock is fixed to the body portion of the pouch all danger of the clock 95 100

falling therefrom is effectively eliminated. The securing means together with the washers 15 are so constructed as not to interfere in the least with the closing of the pouch. 5 In Fig. 2 the pouch is shown as closed, a tab 16 with perforations 17 being provided on the front of the pouch for engaging with a suitable buckle 18. A grille 19, having lattice work 20, is formed in front of the pouch 10 to protect the face of the clock. The cover portion is provided with carrying straps 21, 22, and 23 which are connected to the cover portion by riveting or otherwise securing the same to the rings 24, 25 and 26 respectively. 15 The strap 22 is connected at 27 to strap 23 and serves to maintain the pouch in upright position as the same is being carried about. This results from the fact that as the pouch tends to turn as a whole about the points 28 20 and 29 at which the straps 21 and 23 are secured to the pouch the point 30 to which the strap 22 is secured begins to oscillate about a line between the aforesaid points as a center, and consequently moves the point 30 to 25 which the strap 22 is connected to the pouch away from the point 27 where the said strap 22 is connected to the strap 23. When the pouch is in upright position there is only a small amount of slack, if any, in the strap 30 22. Hence as soon as the pouch begins to oscillate about the points 28 and 29 as a center of oscillation the strap 22 becomes taut and arrests the further movement of said pouch. It will thus be apparent that the 35 amount of oscillation of the pouch which takes place in being carried about depends entirely upon the amount of slack in the strap 22. If there is substantially no slack in said strap there will be substantially no oscillation. 40

In Figs. 3 and 4 I show a slightly different method of securing the clock to the body of the pouch. Instead of passing the securing means through the periphery of 45 the body of the pouch and the clock casing, the former is secured to the latter by passing the securing means through the front of the body portion and through the face of the clock. In this case the grille flange 50 19 serves very admirably the purpose served by the washers 15 in Fig. 2.

It is obvious that slight changes may be resorted to. For instance, it is quite apparent that it is not essential, although preferred, to have the securing means for the clock at the places shown. They may be placed at any point or points on the periphery or may protrude through the front of the body portion. Hence, such changes, 55 and other changes may be made without departing from the true spirit and scope of my invention.

What I claim is:—

1. In a carrying pouch for a watchman's

time register, in combination, a clock, a 65 body portion closed at the upper and side portions thereof to exclude rain or dust, means projecting through said body portion and engaging with the clock to secure said clock in said body portion, a cover 70 imperforate at its upper and side portions hinged to and telescoping over said body portion, two carrying straps connected to said cover portion on the periphery thereof and substantially opposite to each other, 75 and a third strap connected to the periphery of said pouch and substantially midway between the aforesaid straps.

2. In a carrying pouch for a watchman's 80 time register, carrying means for said pouch comprising two straps connected to the periphery of said pouch, said connections being at a distance from each other, and a single strap located also on the periphery of the pouch substantially midway between the 85 aforesaid straps and connected to one of the aforesaid straps to maintain the pouch normally in upright position and to avoid undue oscillation of the pouch.

3. In a carrying pouch for a watchman's 90 time register, in combination, a recording clock, a substantially circular shaped closure for the clock made in two parts, one part adapted to fit over the clock, means passing through said closure for securing the 95 clock securely therein, the other part of the closure adapted to telescope over the first part of said closure member, a hinge adapted to secure together the parts of the closure, a strap member upon one of the parts 100 of the closure and a buckle secured to the other part of the closure for maintaining part of the closure in adjusted relation, straps having their ends secured in the periphery of the outer closure part and on 105 opposite sides thereof, and a third strap secured at one end to the periphery of the outer closure member midway between the points of securement of the other strap members and having its other end secured 110 to one of the other straps to maintain the closure normally in an upright position and to avoid undue oscillation of the pouch.

4. A carrying pouch for a watchman's 115 time register, comprising in combination, a recording clock, a substantially circular shaped closure for the clock made in two parts and having its ends substantially flat, one part adapted to fit over the lock, the other part adapted to telescope over the 120 first mentioned part, a hinge adapted to secure the parts together, means upon the parts of the closure for maintaining them in adjusted relation, means passing through the telescoped portion of the casing into 125 the clock for securing the clock thereto, an opening in the front end of the closure to give a view of the front of the clock, means

in said opening to protect the clock from injury, two long straps having ends secured to pass over the shoulder of a watchman, and a short strap having an end secured in the periphery of the outer part of the closure and having its other end secured to one of the long straps between its ends to maintain the closure normally in an upright

position and to avoid undue oscillation of the closure and the clock carried thereby. 10

In testimony whereof I affix my signature in the presence of two subscribing witnesses.

CHARLES H. JENKINS.
